UNITED STATES PATENT OFFICE.

EDWARD JAMES SHAUGHNESSY, OF BROOKLYN, NEW YORK.

TOWEL-CABINET.

1,345,262.

Specification of Letters Patent. Patented June 29, 1920.

Application filed January 14, 1920. Serial No. 351,444.

To all whom it may concern:

- Be it known that I, EDWARD J. SHAUGHNESSY, a citizen of the United States, and a resident of the city of New York, borough 5 of Brooklyn, in the county of Kings and State of New York, have invented a new and Improved Towel-Cabinet, of which the following is a full, clear, and exact description.
- 10 This invention relates to improvements in towel cabinets, an object of the invention being to provide an improved support for a continuous towel strip which facilitates the use of the strip and prevents contact of 15 clean portions of the towel with dirty portions thereof.

A further object is to provide a towel cabinet which will be economical in that the portions of the towel which are in use are 20 maintained in a smooth condition and the dirty or soiled portions of the towel are maintained out of contact with the clean, fresh portions thereof.

A further object is to provide a towel cabinet which can be conveniently and easily 25 operated to present clean portions of the towel strip as may be desired and present a neat and attractive appearance at all times and prevent undue waste or extravagance in 30 the use of the towel.

With these and other objects in view the invention consists in certain novel features of construction, and combinations and arrangements of parts as will be more fully 35 hereinafter described and pointed out in the claims.

In the accompanying drawings—

Figure 1 is a perspective view illustrating 40 my improved towel cabinet in use;

Fig. 2 is a view in vertical longitudinal section on the line 2—2 of Fig. 1;

Fig. 3 is a top plan view of the cabinet with the cover, towel and guide plate removed;

Fig. 4 is a view in vertical section on the line 4—4 of Fig. 2; and

Fig. 5 is an enlarged view in elevation illustrating my improved arrangement of gear wheels.

50 1 represents the casing of my improved cabinet which is preferably, although not essentially, of sheet metal and of general rectangular shape having at its front and at its upper end a forward projection 2 which overhangs a towel space and prevents dirt and dust from falling onto the

towel. The sides 4, 4, of the cabinet project beyond the front 3 of the cabinet and have inwardly projecting supporting flanges 5 on which vertical guide rods 6 are secured. These guide rods 6 at their upper ends are fixed to angle brackets 7 and they are spaced from the sides 4 and also spaced from the front of the cabinet for the accommodation of a roller 8 which they support. 65 This roller 8 may be of wood or other suitable material and is mounted to turn on a rod 9 having eyes 10 at its ends, said eyes 10 positioned on the rods 6 and movable vertically thereon, yet maintaining the roller 70 in horizontal position at all vertical adjustments.

A frame 11 is removably mounted in the upper portion of the cabinet and has a fixed bottom plate 12 and a removable guide plate 13 which constitutes a receptacle as well as a support for a towel roll 14. This towel roll may be of any desired material constituting a strip closely wound in the form of a roll. 80

The frame 11 supports a pair of rubber covered or other friction rolls 15 located in a plane in advance of the rods 6 and said frame 11 also supports a pair of friction rolls 16 which are located in a plane in rear 85 of the rods 6 and above the front 3 of the cabinet which terminates at the bottom of the frame 11, but is entirely hid from view by the towel and also by the overhung projecting portion 2 at the top of the cabinet. 90 A pair of intermeshing gear wheels 17 are fixed to turn with the rolls 15 and a pair of intermeshing gear wheels 18 are fixed to turn with the rolls 16 and these gears 17 and 18 are located on the outside of the 95 frame 11, an ample space being provided for their accommodation in the cabinet, as clearly shown in Fig. 3.

A drive shaft 19 is mounted in the frame 11 and carries a relatively large gear wheel 100 20 which meshes with one of the gear wheels 17 and one of the gear wheels 18 and is provided with a pawl 21 to permit turning movement in one direction only. This shaft 19 projects through a recess 22 in the side 105 of the cabinet and is provided at its outer end with a crank 23 to turn the same. A removable cover 24 normally closes the top of the cabinet and is provided with a knob 25 to facilitate its manipulation. 110

The operation is as follows: The towel roll 14 is positioned in the frame 11 and

one end of the towel is projected between the rolls 15, thence downwardly around the roller 8, thence upwardly and between the rolls 16 and thence downwardly into the cabinet. When a person desires to use the towel, he grasps the front run of the towel and uses the same, and during such use he will naturally draw this front run of the towel forwardly causing the roller 8 to elevate, the latter being guided in such movement by the eyes 10 and rods 6. When the towel is released, the roller 8 will fall of its own weight and bring the front run of the towel into a straight or taut position and maintain the same in this position until the towel is again used.

When a section of the towel becomes soiled, the crank 23 is operated to simultaneously turn all of the rolls 15 and 16, thus not only feeding the clean portion of the towel strip forwardly, but also moving the dirty portion of the towel strip into the cabinet where it collects as shown in Fig. 2.

The soiled portion of the towel strip is always in rear of the clean or front run thereof and these two runs of the towel are maintained spaced apart by the weight of the roller 8 as indicated clearly in Fig. 2. Hence, there is no danger of the soiled portion of the towel coming in contact with the clean portion of the towel and this is of extreme importance in the prevention of contagion as each person using the towel is insured of a clean portion thereof which has been maintained out of contact with all other portions of the towel previously used.

While it is desirable that the crank 23 be operated to feed the towel, it is obvious that a pull on the towel would cause the turning movement of all four of the rolls and thus feed the towel, and the only danger of this operation is the tendency to unevenness of the feeding action and crinkling of the towel.

It will be noted that after the towel strip is once set in operative position, the roller 8 will maintain the towel in a smooth, attractive and convenient position.

Various slight changes may be made in the general form and arrangement of parts described without departing from the invention, and hence I do not limit myself to the precise details set forth, but consider myself at liberty to make such changes and alterations as fairly fall within the spirit and scope of the appended claims.

I claim:

1. A towel cabinet, comprising a casing, side walls on the casing projecting beyond the front of the casing, an extension on the upper portion of the casing extending forwardly, whereby a towel space is formed between the projecting side walls of the casing below the extension, a pair of vertical rods located in said towel space, a roller

having vertical movement on said rods, and two pairs of friction rolls supported in the casing adjacent the extension and adapted to support and feed two runs of a towel located at opposite sides of the first-mentioned roller and normally held spaced apart by said roller.

2. A towel cabinet, comprising a casing, side walls on the casing projecting beyond the front of the casing, an extension on the upper portion of the casing extending forwardly, whereby a towel space is formed between the projecting side walls of the casing below the extension, a pair of vertical rods located in said towel space, a roller having vertical movement on said rods, two pairs of friction rolls supported in the casing adjacent the extension and adapted to support and feed two runs of a towel located at opposite sides of the first-mentioned roller and normally held spaced apart by said roller, and means for simultaneously turning all of said friction rolls.

3. A towel cabinet, comprising a casing, side walls on the casing projecting beyond the front of the casing, an extension on the upper portion of the casing extending forwardly, whereby a towel space is formed between the projecting side walls of the casing below the extension, a pair of vertical rods located in said towel space, a roller having vertical movement on said rods, two pairs of friction rolls supported in the casing adjacent the extension and adapted to support and feed two runs of a towel located at opposite sides of the first-mentioned roller and normally held spaced apart by said roller, and a partition in said casing dividing the same into upper and lower compartments, said upper compartment adapted to receive a supply roll, and said lower compartment adapted to receive the soiled portion of the towel.

4. A towel cabinet, having a towel space at the front thereof, a pair of vertical rods in the towel space, a horizontal roller, a rod supporting the horizontal roller, eyes on the ends of the last-mentioned rod movable on the first-mentioned rods, and two pairs of friction rolls located adjacent the upper portion of said towel space, and between said pairs of friction rolls two runs of a towel are adapted to be respectively located when said towel is positioned around the first-mentioned roller and held taut by the weight of said roller.

5. A towel cabinet, comprising a casing, two pairs of friction rolls supported in the casing and adapted to feed a towel strip between them, gear wheels secured to turn with the friction rolls, a drive gear wheel driving all of said first-mentioned gear wheels, a pawl engaging the drive wheel permitting its turning movement in one direction only, means connected to the last-

mentioned gear wheel for operating the same, a weighted roller having vertical movement in the cabinet, and a towel strip located between said friction rolls and under said weighted roller.

6. A towel cabinet, comprising a casing, two pairs of friction rolls supported in the casing and adapted to feed a towel strip between them, gear wheels secured to turn with the friction rolls, a drive gear wheel driving all of said first-mentioned gear wheels, a pawl engaging the drive wheel

permitting its turning movement in one direction only, means connected to the last-mentioned gear wheel for operating the same, a weighted roller having vertical movement in the cabinet, and a towel strip located between said friction rolls and under said weighted roller, said cabinet having a compartment receiving the soiled end of the towel strip and having a compartment at its upper end for the roll supplying the strip.

EDWARD JAMES SHAUGHNESSY.
